Patented Apr. 13, 1920.

Inventor:

A. H. Stamm,

By L. M. Hubbard
Atty.

UNITED STATES PATENT OFFICE.

ALFRED H. STAMM, OF PEORIA, ILLINOIS.

DESIGN FOR A TOY VEHICLE.

54,872.

Specification for Design. Patented Apr. 13, 1920.

Application filed September 11, 1919. Serial No. 323,228. Term of patent 7 years.

To all whom it may concern:

Be it known that I, ALFRED H. STAMM, a citizen of the United States, residing at Peoria, in the county of Peoria and State of Illinois, have invented a certain new, original, and ornamental Design for a Toy Vehicle, of which the following is a specification, reference being had to the accompanying drawing, forming part thereof.

The figure shows, in perspective, a toy vehicle illustrating my new design.

I claim:

The ornamental design for a toy vehicle, as shown.

In testimony whereof I affix my signature in presence of two witnesses.

ALFRED H. STAMM.

Witnesses:

J. B. WOLFENBARGER,
L. M. THURLOW.
